The ornamental design for a power control box of an LED string light, as shown and described.

DESCRIPTION

See application file for complete search history.

FIG. 1 is a front elevation view of a power control box of an LED string light, showing our new design;

FIG. 2 is a rear elevation view thereof;

FIG. 3 is a left-side elevation view thereof;

FIG. 4 is a right-side elevation view thereof;

FIG. 5 is a top plan view thereof;

FIG. 6 is a bottom plan view thereof;

FIG. 7 is a front perspective view thereof; and,

FIG. 8 is a rear perspective view thereof.

The broken lines depict portions of the article that form no part of the claimed design.
